UNITED STATES PATENT OFFICE.

JOSIAH LETCHWORTH, OF BUFFALO, NEW YORK.

DESIGN FOR TUG-CLIPS.

Specification forming part of Design No. 6,883, dated September 16, 1873; application filed April 28, 1873.
[Term of Patent 14 years.]

To all whom it may concern:

Be it known that I, JOSIAH LETCHWORTH, of the city of Buffalo, in the county of Erie and State of New York, have invented a Design for Tug-Clips, of which the following is a specification:

My design relates to the shape or configuration of an article of manufacture commonly known as tug-clip, employed in harness for connecting the tugs or traces with the hame-staples.

The design is fully represented in the accompanying drawing, in which Figure 1 is a plan view, and Fig. 2 a side elevation, of a tug-clip.

Like letters designate like parts in each of the figures.

A represents the ring-shaped front part of the tug-clip engaging with the hame-staple, and B B the flat ends or jaws which extend therefrom, and between which the front end of the tug or trace is secured by rivets passing through holes b b. The contour of the

portion A (looking edgewise at the jaws B B) is formed by two eccentric circles, c d, as clearly shown in Fig. 1, so that the thickness of the portion A diminishes gradually from its middle toward the jaws B B, its thickest portion lying in a line drawn centrally between and parallel with the said jaws. The thinner portions of the ring A are curved outward, so as to form a sharp corner at their junction with the jaws B B, as shown at e, Fig. 2, and the sides of the eye taper toward the jaws, as seen at f g, whereby a neater appearance of the article is produced.

I am aware that tug-clips in which the ring-shaped portion A is made of the same thickness throughout have been in common use.

What I claim as my invention is—

The design for a tug-clip, as herein shown and described.

JOSIAH LETCHWORTH.
